Wilbur D. Canaday, Stamford, Conn., assignor to Lenthalic Incorporated, New York, N. Y., a corporation of New York

Application July 3, 1935, Serial No. 57,511

Term of patent 7 years

To all whom it may concern:

Be it known that I, Wilbur D. Canaday, a citizen of the United States, residing at Stamford, in the county of Fairfield and State of Connecticut, have invented a new, original, and ornamental Design for a Dropper Shell or the like, of which the following is a specification, reference being had to the accompanying drawing, forming part thereof.

In the drawing:

Fig. 1 is a front view of the dropper shell or the like of my design;
Fig. 2 is a side view; and
Fig. 3 is a top view.

I claim:

The ornamental design for a dropper shell or the like, substantially as shown.

WILBUR D. CANADAY.
